UNITED STATES PATENT OFFICE.

ELMER A. SPERRY, OF CHICAGO, ILLINOIS.

DYNAMO-ELECTRIC MACHINE.

SPECIFICATION forming part of Letters Patent No. 354,946, dated December 28, 1886.

Application filed March 21, 1884. Serial No. 125,005. (No model.)

To all whom it may concern:

Be it known that I, ELMER A. SPERRY, a citizen of the United States, residing at Chicago, in the county of Cook and State of Illinois, have invented certain new and useful Improvements in Dynamo-Electric Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to that class of dynamo-electric machines having cup-shaped electro-magnets with their opposite polar faces in the form of continuous circles, between which an annular drum-shaped armature is arranged to operate.

The invention consists in the construction and arrangement of parts, which will be hereinafter more fully described, and then set forth in the claim.

In the drawings, Figure 1 is a longitudinal section of a magneto-electric machine. Fig. 2 is a detail showing means for communicating motion to the armature.

The reference-letter A designates two shell-shaped electro-magnets, which have solid end heads, and are chambered for the reception of a solid core-piece, A'. The abutting open ends of the shells A are provided with flanges a, for bolting the same together, and the interior of the two connected shells constitutes a continuous circular pole-face, opposite which is the concentric solid core A, the two parts thus arranged thus forming opposite polar surfaces in the form of continuous circles, which are concentric, or one within the other, as shown by letters N S N S. Between these concentric surfaces is arranged a cylindrical or annular armature, B, to the ends of which are secured circular plates D' D², forming end heads for said armature. The peripheries of these plates are provided with continuous grooves for the reception of driving-belts c, which lead to a counter-shaft, as is seen in Fig. 2, and communicate motion to the armature.

The plates D' D² surround shaft-shaped extensions A² of the core-piece A', which are secured to the end heads of the shells A by screw-extensions A³ and nuts A⁴. To the plates D' D² are also secured oblique flanges

J J', which rest upon anti-friction balls b', placed on conducting-rings L on the extensions A² of the core A'. These extensions A² are screw-threaded and receive internally-threaded collars N, which are surrounded by sleeves N' of some insulating material, the function of which is to support the conducting-rings L. The collars are adjustably secured on the shaft by means of jam-nuts O. By supporting the necessarily large bearing-surface of the interior of the rings D D' upon balls b', I obviate all undue friction and insure an unretarded rotation of the armature. These balls are conductors of electricity, and the circuit is from the negative binding-post 70 15, through the conductor 16 to ring L, balls adjoining the disk D², through said disk, the drum B, disk D', and balls adjoining the latter, and from thence by the insulated ring on the shaft through the wire 17 to the positive 75 binding-post 20, and from thence to the field-magnet coils, in a derived circuit, by the conductor 18, and to negative binding-post by the conductor 19.

It should be observed in speaking of the shell-shaped sections A as the electro-magnet that the exterior of these sections is covered with wire coils F and F', connected, respectively, by the wires 19 and 18 with the negative and positive binding-posts 15 20, the coils 85 themselves being connected by means of the wire 25.

It will be apparent that in a machine of the described type all of the active conductor or armature in revolving through the magnetic field is made to cut lines of force of a constant tendency or direction throughout the whole of its revolution, and that the magnet presents a continuous circular polar surface to the action of the armature.

What I claim is—

In a dynamo-electric machine, the combination of the field-magnet having a solid core-piece with shaft-shaped extensions, the conducting-rings fitted on said extensions and insulated therefrom, the anti-friction balls serving as electrical conductors, and the drum-shaped armature supported upon said balls and rotating thereon, substantially as described.

In testimony whereof I affix my signature in presence of two witnesses.

ELMER A. SPERRY.
